United States Patent Office.

JOHN J. EMERY, OF OWL'S HEAD, MAINE.

Letters Patent No. 94,950, dated September 21, 1869.

IMPROVEMENT IN SURGE-RELIEVERS FOR CABLES.

The Schedule referred to in these Letters Patent and making part of the same.

To all persons to whom these presents may come:

Be it known that I, JOHN J. EMERY, of Owl's Head, of the county of Knox, and State of Maine, have invented a new and useful Chain-Cable Safety-Apparatus or Mechanism; and I do hereby declare the same to be fully described in the following specification, and represented in the accompanying drawings, of which—

Figure 1 is a top view, and

Figure 2, a longitudinal section of it as applied to the bow and chain cable of a vessel.

It is well known that a chain cable is very liable to be broken by a sudden draught, or what is termed a "dead strain" of a vessel, brought upon it while the vessel may be at anchor and in movement by the waves.

The purpose of my invention is to ease such strain on the chain cable, so as to prevent its breakage.

In carrying out my invention, I combine with the stop-pawl A and the chain bridge B, two, or any other suitable number of springs, S S.

These springs I arrange to slide on inclined rods *a*, fixed in position upon the deck *b* of a vessel *C*.

The bridge B slides on the bars and against one end of each of the springs, and has the pawl pivoted to it, so as to extend above it, in manner as represented.

Therefore, below the pawl is the bridge or rest B, for the chain to run on.

The springs at their other ends abut against a stationary shoulder-piece or abutments, *d d*, secured to the deck.

The apparatus, as described, I arrange on the deck, and forward of the windlass E, the chain cable, shown at F, being passed from the windlass to and between the pawl and the bed, and next through the hawse-hole of the bow.

On dropping the pawl, so as to cause it to engage with the chain, a strain on the latter, tending to draw the chain out through the hawse-hole, will be counteracted and eased by the springs.

I am aware that it is not new to employ a spring to counteract a strain on a rope or rod, and, therefore, I make no claim to the invention of this in the abstract; but

What I do claim as my invention, is—

The combination and arrangement of the chain-cable pawl A, the bridge B, the spring or springs S S, and their supporting rods *a a*, or mechanism in the whole being to operate substantially as set forth.

JOHN J. EMERY.
